PUMP FOR MOBILE FIRE PUMPERS

Harry E. La Bour, Elkhart, Ind.

Application September 2, 1939, Serial No. 293,227

1 Claim. (Cl. 103—113)

The present invention relates to mobile fire pumpers. Fire fighting equipment, as previously organized, has been developed chiefly for the purpose of protecting buildings and equipment in congested districts. This involves two general provisions, namely, a water supply system, including city water mains to provide the necessary water supply, and elaborate and expensive pumper trucks maintained and manned by professional fire fighters constantly on duty.

The chief object of the present invention is to provide means by which it is possible for a limited personnel, if necessary one man, to transport and bring into operation against a fire a complete high pressure, motor driven fire pumper of effective capacity. In brief, the present invention provides the fire fighting art with a fire department requiring a minimum of personnel, and which is fully effective even with only one man. Obviously, several men can expedite certain of the operations, particularly those of coupling up the hose, nevertheless, one man can quickly transport and bring the unit into full operation.

For the protection of farm buildings, country homes, or even isolated communities, such as villages, small towns, lake cottages, resorts and the like, such previously known provisions are not justified, and in some cases are quite out of the question. The result is that no suitable means for fire fighting in such situations has heretofore been available. While in many such situations ample water is available, no mobile pumping equipment adequate to the needs of fire fighting under those conditions has been developed.

I am aware that heretofore, particularly in Europe, there have been proposals to provide a pumper for fire protection purposes utilizing a centrifugal pump as the pumping and pressure developing means. Since in a mobile fire pumper it is generally necessary to be able to raise the liquid to the pump the usual centrifugal pump requires some additive means to prime the pump to put it into operation and to maintain this prime to continue it in use. Schemes for utilizing the suction of an internal combustion engine or to employ an auxiliary air pump has been proposed, but they are not sufficiently positive and reliable.

Prior art pumper employing centrifugal pumps with priming attachments and auxiliaries are too expensive and intricate. They cost too much in the first place, and are too unreliable and complex for the peculiar requirements of

non-professional fire fighting service. It is generally assumed that skilled personnel will operate the same.

The mobile pumper which is herein disclosed as the preferred form of my invention is intended to be used by either professional fire fighters or by volunteers with complete success. The pumping element is preferably a high pressure single stage self-priming centrifugal pump with only one movable part, i. e., the impeller. The unit is light and small compared with previously known devices. Impurities and entrained solids cannot interfere with the operation of the device. A single person, who is capable of operating an automobile, can hitch an automobile (even the lightest passenger car on the market) to the unit and transport it to the place of use and put it into operation. The concept of rapid automobile transportation by ability to hitch the unit as a trailer to the rear bumper of any passenger automobile gives the unit an availability heretofore unknown in apparatus for this purpose.

The unit is constructed and adapted for high speed transportation behind a passenger automobile without previous preparation since a hitch, having a universal bumper type clamp and universal swivel connection, permits the unit to be hitched to the bumper of any automobile and to be drawn wherever a passenger car can be driven. A notable feature is the roadability or stability on the road of the bumper unit. A trailer chassis preferably having a tread of standard gauge is employed, and by disposal of the parts which involve the major weight practically in the longitudinal median line of the trailer chassis and substantially balanced fore and aft, and with the center of gravity as low as possible a degree of stability and roadability is secured which will allow the unit to go at high speed over substantially any road that is open to the automobile. It can take any road that the automobile can travel at any speed that the automobile can be driven without substantially interfering with the ability of the automobile to cover the ground.

In any fire-fighting equipment reliability is of the utmost importance. Reliability means that the equipment must be ready to go at any instant and that when the equipment has been gotten to the fire it will work immediately, and do the intended service quickly and efficiently.

Considered from the standpoint of a loaded vehicle, the present unit is designed with a low center of gravity with the weight properly ar-

ranged for great stability and capable of high speed transportation. The concept is more easily grasped by pointing out that in the preferred embodiment the center of gravity of the pumper is substantially as low as or lower than the center of gravity of the automobile without any load. This is attained by disposing the chassis frame at substantially the level of the wheel axis, and disposing the pump and engine on the frame with their bottoms at substantially the same level as the bottom of the frame.

This means that the unit can be taken, from the place where it is normally kept, to the point of the fire in minimum time. Because of the mobility of the unit a widely scattered community or group of buildings may rely upon this single inexpensive unit.

From the standpoint of operation as a pumper the simplicity and inherent reliability of the unit is outstanding. The pump has only one moving part which is the impeller and its shaft. The driving motor is preferably a compact self-contained multi-cylinder internal combustion engine arranged for operation under governor control at various desired speeds, and particularly at a relatively high speed of the order of 3000 R. P. M., so that it is compact and powerful for its weight. The pump is essentially of the self-priming centrifugal type. In the preferred form it employs the hydraulic balance or peripheral reentry principle in its operation of priming and pumping. The pump, in order to constitute an adequate fire-fighting unit, must develop pressures of the order of 100 pounds per square inch or above, and must deliver a gallonage which will be effective. The present unit will discharge 150 gallons per minute at 100 pounds per square inch pressure, with the engine running at approximately 2850 R. P. M. This capacity is more or less a standard requirement to meet present day insurance requirements and equipment standards as an effective pumper. The simplicity and inherent self-priming ability of the present pump, together with its rapid self-priming, provides a fire-fighting equipment of great simplicity, reliability and effectiveness, which are essential for operation by the non-professional type of operator which must be relied upon to operate the unit.

The hydraulic balance type of self-priming pump is desirable for a number of reasons, some of which are as follows: This type of pump inherently regulates its own internal operation to expel the air as rapidly as possible consistent with retaining its vacuum. It is free of any delicate parts, such as valves or small passageways which tend to get out of order or become stopped up by impurities in the water or otherwise become disabled. Since internal reversal of flow occurs in both the priming and in the main passageways where two passageways are used, the pump tends to keep itself clear of internal obstructions. The same advantage of being self-clearing is present in the single throat type. A bypass between discharge and suction portions of the impeller has pressure always in one direction and tends to become stopped up and hence become inoperative. An open by-pass between discharge and suction portions of the pump if large enough to produce rapid priming completely destroys the efficiency of the pump when operating at such high pressures as are here required. Air entering the suction pipe does not cause the self-priming pump to become air bound.

A necessary part of the self-priming centrifugal pump is the charge of liquid employed to

effect self-priming. This is normally trapped within the body of the pump and its separator and intake trap, and provision is made to insure that that charge will be retained either within the pump or in an associated container when the unit is carried over the roughest of roads and subjected to vibration, turning corners, and bouncing over obstructions. Even in the case of accidental overturn, the liquid will be retained in the pump or in the associated container and be instantly available for service when called upon to operate even in cold weather. The operator may start the engine of the unit before making the run. It may be easier to start the engine before leaving the fire house or other storage place of the unit, and such starting of the engine may save the time of warming up while making the run. Under those circumstances, the means for retaining the priming charge is particularly desirable. This means does not, however, interfere in any way with the starting or running of the engine to warm it up.

For use under cold weather conditions when water would tend to freeze in the pump, the priming charge may consist of an anti-freeze solution. Alternatively, for use in winter time in cold climates, the charge of priming liquid consisting of an anti-freeze solution or mixture, may be carried with the pump in a separate can or container which is definitely associated with the pumper, so that it will be available to serve as the priming charge when the pumper arrives at the place of use.

The pump in the preferred form is specially designed to develop the necessary high pressure in a single stage and within small dimensions and to operate at high efficiency. This is of the utmost importance, since weight and space must be kept at a minimum. The preferred form of pump herein shown is particularly designed and constructed for the present service to secure the necessary delivery pressure and volume in a small compact high speed device and to secure rapidity of priming. The particular unit herein shown will prime itself in sixteen seconds when using the full twenty-four feet of standard 3 inch suction hose with a 10 foot suction lift from the surface of the water to the pump. The speed of priming is important inasmuch as even a few seconds count in first getting water upon the fire.

A feature of the unit herein disclosed is that it is completely self-contained as to all the equipment necessary to take water from the source and deliver it onto the fire. The present unit is arranged and designed to carry the necessary length of suction hose and the necessary length of discharge hose with suitable wrenches, nozzles and strainer. Preferably, space is provided for 500 feet of 1½ inch fire hose and two twelve foot lengths of 3 inch suction hose with a suitable strainer, all with standard couplings. If desired, 250 feet of two inch fire hose may be substituted.

Numerous features of novelty are involved in the production of the present pumper, and the outstanding novelty is the coordination of a number of features to make a practical device able to meet the demands of a wide field.

From my study of the prior art both in this country and in Europe, I believe it is broadly new to provide in a mobile pumper a compact, self-priming centrifugal pump of the type herein disclosed and having sufficient capacity and delivery pressure to serve as a fire pump and at the

same time be light and compact enough as a mobile pumper to be transported by hitching onto the bumper of any standard passenger automobile, and travel at substantially any speed and over substantially any road that the automobile can travel, and arrive at the fire in immediate operating condition, and which is capable of being transported and put into operation expeditiously by one man.

The pumper herein disclosed as the preferred form of my invention provides therefore the following main features of novelty:

1. The unit has low enough weight and low enough center of gravity to be able to travel virtually as a part of a passenger automobile.

2. The unit is constructed so that hauling or rough handling will not incapacitate it or interfere with the adequate performance of any of its intended functions.

3. The unit provides a compact but convenient assembly of all the necessary equipment for throwing water upon the fire so that nothing will be lost or forgotten.

4. The unit embodies a pump which is of the simplest possible type with nothing that can be injured or interfered with by the conditions under which it must work.

5. The unit comprises a centrifugal self-priming pump preferably of the hydraulic balanced type, employing a charge of priming liquid and having means for associating the necessary charge of priming liquid with the pump so that the pump may promptly be put into operation to evacuate its suction pipe when the need arises.

6. The unit has sufficient power and capacity to be effective for fires in such buildings as would be found in farms, summer resorts, farm homes and small communities.

7. The unit is capable of being transported and operated by one man.

Now in order to acquaint those skilled in the art with the manner of constructing and operating my invention I shall describe, in connection with the accompanying drawings, a specific embodiment of the same.

In the drawings:

Figure 1 is a perspective view from the left and front side of the unit of a mobile fire pumper embodying my invention;

Figure 2 is a perspective view taken from the right rear of the unit;

Figure 3 is a longitudinal vertical section through the unit;

Figure 4 is a fragmentary vertical sectional view through the packing gland of the unit;

Figure 5 is a fragmentary vertical section through the throating of the pump taken on the line 5—5 of Figure 6;

Figure 6 is a section taken on the curved line 6—6 of Figure 5;

Figure 7 is a fragmentary development of the main throat opening shown in Figure 5; and

Figure 8 is a view similar to Figure 7 of a modified form of throat opening.

The unit herein shown comprises a main chassis frame 1 supported on semi-elliptical vehicle springs 2—2, these in turn being supported upon a drop axle 3 carrying road engaging wheels 4—4. The frame 1 lies at approximately the level of the axis of the road wheels 4—4. The wheels 4—4 are preferably provided with pneumatic tires and are mounted in known manner through suitable anti-friction bearings upon spindles forming the ends of the axle 3. Suitable fenders or mud-guards 5 are connected to the

frame and extend over the tops of the wheels 4—4. The main frame 1 comprises a generally rectangular main portion having longitudinal sills 6—6 along the outer sides, these sills being extended forwardly and converging to form a relatively narrow frame or tongue 7 which, at its front end, is provided with a universal joint or swiveled connection 8 the rear end of which is connected to the tongue and the front part of which is connected to the universal bumper hitch or clamp 9 which is arranged to be attached to any standard or usual automobile bumper bar and securely fastened thereto. The specific form of bumper bar clamp may obviously be varied. 15 If desired, safety chains may connect the bumper bar clamp to the tongue 7 to supplement the universal coupling 8.

A cross bar handle 10 at the front of the tongue provides means for manually moving the unit 20 as may be necessary to raise or lower the tongue 7 for connection of the bumper bar clamp 9 to the automobile. A leg 12, with a suitable foot 13, extends through a bracket at the front of the tongue 7 and a clamp is provided for holding the leg in any adjusted position. In like manner, an adjustable leg 16 with its foot 17 is disposed in a bracket 18 connected to the transverse frame member 15 at the rear of the unit. This leg is likewise adjustable and retractable. When the unit is prepared to travel the legs 12 and 16 are raised to their uppermost positions, from which they cannot escape by virtue of a lock of known form, and when the unit is to be set into position to operate to pump 35 liquid the legs 12 and 16 are lowered to engage the ground and hold the frame 1 in substantially level position. The length of the frame is such, both forward and rearwardly of the axle, that the unit cannot tip up or down to an undesired 40 angle, since that would make it difficult for the operator to restore it to the level condition.

The two longitudinal sills 6—6 are connected together by the transverse frame member 14 at the front end or tongue portion and by the transverse frame member 15 at the rear end, and additionally they are connected together by cross frame bars 19 and 19a which constitute braces for the frame, and more particularly the cross bar 19 has a bracket 20 which forms a perch for the front end of the engine 22. The cross bar 19a provides a support for the rear end of the engine 22 and the front of the pump 24. A pair of supplemental longitudinal bars or sills 25—25 carry a cross bar 26 which supports the rear end of the pump 24, a suitable pad or foot 27 under the trap 28 of the pump 24 being provided to support the rear end thereof. Supplemental sills 25—25 serve in conjunction with the main longitudinal sills 6—6 to support the hose wells 30—30 which are arranged on opposite sides of the intake trap 28.

The engine 22 is a compact, self-contained power plant comprising a four cylinder four cycle engine housed within a suitable hood or cover 31 at the front of which there is provided a cellular radiator 32 with its filler cap 33. In the upper part of the hood 31 there is housed a fuel tank provided with a filler cap 34. The exhaust from the manifold is led up through the hood 31 to a muffler 35 at the top of the engine unit. A carburetor 36, provided with a drain and connected between the fuel tank and the intake manifold of the engine supplies the engine with fuel.

A suitable crank 37 is carried with the engine 35 and a starting control is conveniently placed near

the handle as indicated at 38. The engine is provided with a speed governor and the adjustment for the control of the speed governor is provided with an external operating knob 39, whereby the speed of the engine may be regulated. For example, during the warming up period the speed may be relatively low and, upon bringing the pump up to pressure, the speed may be increased to approximately 3000 R. P. M.

The engine has its own internal oiling system, as provided through a sump 40 in the crank case. The rear end of the crank case and frame of the engine is extended in the form of a bell housing to contain the flywheel and providing a suitable bolting flange for receiving the front end of the open circular bracket 43, the rear end of which is bolted to a boss 44 on the main frame 45 of the pump 24. The main frame 45 of the pump contains the impeller chamber in which is disposed the impeller 46, this impeller being mounted upon the impeller shaft 47. The impeller shaft 47 at its rear end has a disc 48 welded thereto and the disc, in turn, is bolted to the flywheel 49 of the engine 22, so that the impeller shaft 47 forms, in fact, a rigid extension of the crank shaft to the engine. The pump body 45 is provided at its upper end with a neck 50 which terminates in a bolting flange 52 to which is bolted the corresponding flange 53 of the separator 54. The main pump body 45 provides a concentric type of casing for the open impeller 46 and it provides, in the neck portion 50, the main discharge passageway 55 and an auxiliary or priming passageway 56. The impeller 46 sweeps the concentric casing with not substantially more than mechanical clearance of about $\frac{1}{8}$ " on the side, and a tip clearance of approximately $\frac{3}{32}$ " in the particular embodiment here shown, although this may vary for different sizes of pumps. The main and auxiliary passageways 55 and 56 in the neck 50 have corresponding mating passageways (not shown) in the lower part of the separator 54. The pump is of the type disclosed in my prior Patent 1,578,236 and its detailed structure and mode of operation are fully disclosed in my co-pending application, Serial No. 289,757, filed August 12, 1939, now matured into Patent 2,291,478 of July 23, 1942, to which reference is hereby made.

The separator 54 comprises a hollow body in which the mixture of air and water discharged from the impeller to the main throat and passageway 55 during priming, carries air out of the pump casing and evacuates the suction line during priming. This separator 54 has a central top opening by way of the elbow fitting 58 and vent pipe 59 which is left open at all times, this vent pipe leading down to a point below the adjacent operating parts and permitting the evacuation of air during priming when the discharge of the separator 54 is closed. The pipe being open also permits the discharge of water when the separator 54 is under water pressure, but the tube is so small and the flow constriction so great that the escape of water here is negligible. A flexible tube 60 is connected to the inside of the separator and leads to a pressure gauge 62, which is mounted on the back side of the separator 54, as will be apparent from Figure 2. The separator 54 has an outlet boss 63 in which there is threaded a fitting 65 having two branches 65-65 each provided with a shut-off cock 66-66 and each branch having a threaded outlet covered by a cap which is internally threaded to fit the threads of the outlets, the threads of the outlets being

standard fire hose coupling threads adapted to receive the female couplings 67-67 of the lengths of hose 68-68 carried in the hose wells 30-30. The threaded caps 69 are tethered by means of short lengths of chain 70 to the corresponding branch outlet 65, so that the same may not become lost.

The primary purpose of the pressure gauge is to show when the pump has filled itself with liquid by emptying the air from the suction pipe and is ready for discharging water. The secondary purpose is to indicate whether the pump is giving the desired pressure upon the hose and nozzles when the pump is employed in actually throwing water upon the fire. During the time that the pump is evacuating the suction pipe, that is, while it is pumping air, the pressure in the separator does not rise substantially above atmosphere because of the open air vent. As soon, however, as the air has been evacuated from the suction pipe, and the pump filled with liquid, the valves 66 being at this time closed the outflow of liquid from the separator through the air vent is so greatly restricted as to be negligible, and consequently, the pressure in the separator rises sharply at the moment that the pump has attained its prime. This is a very useful indication.

The hose wells each contain four rolls of $1\frac{1}{2}$ " standard fire hose, each roll containing 50 feet, and the rolls being held in place by partitions between adjacent rolls, these partitions being parallel sheet metal partitions. The rolls are further held in place by flexible straps or bands 72 fastened at each side to the sides of the cylindrical or drum-shaped hose wells and buckled together to hold the rolls of hose definitely in shape.

The body 45 of the pump in which the impeller chamber is disposed has a cylindrical recess upon the back side of which is formed the boss 44 heretofore mentioned and also a boss 72 which is bored out to provide space for the fibrous packing 73, which is held in place by a follower 74 which has an intermediate lubrication connection by way of the tube 75 and grease cup 76. The rear of the follower 74 is counterbored to provide space for the supplementary packing 77, and the grease from the grease cup 76 is introduced into an annular chamber between the two packings 73 and 77 to lubricate the main packing. An auxiliary spring pressed follower 78 engages the auxiliary packing 77 which seals off the lubricant chamber. This auxiliary follower 78, which is free to move along the length of the shaft 47, is pressed against the auxiliary packing 77 by means of the coil spring 79, which is under compression. The opposite end of the spring presses against a flange 80 in a threaded sleeve 82, which sleeve is threaded into a central hub 83 formed in the cylindrical mounting bracket 43. The sleeve 82 has at its front end a head which is provided with capstan openings 84 into which a pin may be inserted to turn the sleeve 82 upon the threads in the hub 83, to thereby advance it towards the follower 74 or to retract it.

The operation of this sealing device is believed to be apparent from the above. The threaded sleeve 82 which contains the compression spring 79 provides a spring abutment for the spring 79 whereby the spring may force the auxiliary follower 78 against the auxiliary or sealing packing 77 in the main gland follower 74 and this gland follower 74, in turn, is pressed against the main packing 73 on the pump

shaft 47 to seal it against passage of fluid along the shaft.

Now the present pump is designed to operate either as a suction pump, to raise water from a lower level by the self-priming action, or it may be used as a booster pump by hitching the inlet, later to be described, to a hydrant, whereupon the pressure prevailing in the impeller chamber will be a very substantial pressure above atmospheric. In fact, it is not at all unusual to have pressures of the order of 50 to 60 lbs. on a fire hydrant and unless some means were provided to prevent it, the pressure of the water inside the pump might blow the packing 73 and the follower 74 out of the recess in the hub 72 and thereby unseal the pump. Obviously, it would not do to put so high a spring pressure on the follower as to overcome this pressure, for then if the pump were operating on a suction the spring pressure would be excessive, the shaft would heat and score, and the pump might be damaged. The sleeve 82 and its auxiliary spring pressed packing gland follower serves to meet this troublesome problem, in that the spring 79 is put under a definite predetermined stress, that is, it is pre-stressed by a definite amount, and the sleeve 82 is long enough to reach the main gland follower 74 and thereby limit further stressing of the spring 79, but to apply a direct pressure to the said follower 74 by engaging the same endwise. Now it can be seen that by the engagement between the head of the sleeve 82 and the follower 74, internal pressure on the pump cannot blow the packing 73 out because the gland follower 74 is rigidly supported by the sleeve 82. As soon as internal pressure is relieved, then the spring 79 again resumes control of the pressure which is applied to the packing 73, since the sleeve 82 is not resilient and will not follow up except as it is advanced on the threads. As the packing wears, the spring follower 78 will automatically take up the wear and will push the main gland follower 74 away from the head of the sleeve 82, and this gap may be taken up from time to time, but if the pump is put under pressure at such time as a gap exists between the follower 74 and the head of the sleeve 82, no greater injury is done than to shift the follower 74 back against the abutment of the sleeve 82. This arrangement of positive abutment and spring follower is highly advantageous for this service or, in fact, for any desired service where the pump may be subjected to internal pressures of greater or less values than atmosphere.

The cylindrical recess in which the impeller 46 is disposed is closed on the rear side by an inlet and side plate 84 having a tubular neck 85 defining the inlet passageway from the inside of the trap 28. The outer margin of the side plate member 84 has a flange 86 which is engaged by the annular flange 87 of the inlet trap 28, the flange of the inlet trap 28 and the margin of the main pump body 45 being held together by suitable bolts, such as 88 as shown in Figure 4. The inlet trap is provided with a cap or cover 89, at its upper end, this closure 89 closing a cleanout opening and being held normally in place by a C-clamp 90 and a clamping screw 91. A basket-shaped inlet screen 92 is disposed in the trap directly below the cleanout opening and is intended to strain out such solids as would tend to interfere with the operation of the pump itself. This strainer is desirable particularly since the suction of the pump may be disposed in any casual water.

The inlet trap 28 and the pump body are pro-

vided with drains 93 and 94, respectively, for draining the pump, particularly for cold weather.

The inlet trap 28 has an inlet connection 95 into which is threaded a nipple 96 bearing at its outer end a standard suction hose fitting 97 provided with threads adapting the same for co-operation with the internally threaded cap 98 which normally closes the inlet connection, or for connection with the female hose coupling 99 of the suction hose 100, or, alternatively, with the female connection 99 of the suction hose length 102. The hose lengths 100 and 102, respectively, are preferably 12 ft. lengths of standard 3" fire engine suction hose, the lower length 102 bearing at its outer end a suction strainer 103 provided with a large number of slots, in accordance with known practice in the art. The remote end of suction hose length 100 is provided with a male threaded coupling 104 so that the two lengths 100 and 102 may be connected in series to the intake of the pump. The nipple 96 is not essential, but preferably it is of a length which will carry the threaded male fitting out to a point beyond the adjacent hose wells 30-30 so that a suitable spanner wrench which is employed for coupling fire hose may be applied and used without interference from the hose wells. The intake connection 95 lies well above the frame 1 where it is readily accessible at all times.

The two lengths of hose 100 and 102 are bent into U-shape and the bottom of the U is placed in front of the radiator 32 of the engine, this being desirable, first of all, to protect the radiator from material thrown up from the road in course of the run, and also tending to insure that the hose will not be shaken off in the event that the flexible straps which hold the hose in place should become loosened. The sides of the U-shaped lengths of hose preferably rest upon hose boxes 105-105 which are disposed longitudinally of the side frame sills 6-6 and which are adapted each to contain a length of 50 ft. 1½" hose. Obviously, instead of carrying 500 feet of 1½" hose, a shorter length of a larger diameter hose, such, for example, as 250 feet of 2" hose, may be substituted.

The specific arrangement of the partitions in the wells 30-30 and the size of these wells may be varied, within suitable limits. Flexible straps 50 attached to the frame are buckled over the boxes 105 and the adjacent lengths of hose, as indicated at 106 in Figures 1 and 2, and the front part of the suction hose may be carried in fork-shaped brackets mounted on the frame 1, suitable flexible straps such as 107 going over the hose to hold the same in position. The hose wells 30 are located aft of the axle 3 and the hose supported in these wells therefore tends to make the unit unbalanced. However, the suction hose, 60 which is quite heavy, extends around and completely in front of the engine 31, as will be seen in Figure 1, and tends to counterbalance the hose in the wells in the rear. Thus with the engine pump unit substantially balanced over the axle, 65 and the hose likewise substantially balanced fore and aft over the axle, the unit is, whether in use or in transport, substantially in balance over the axle, and therefore at all times relatively stable.

The pump, as above mentioned, is fully disclosed in my copending application, Serial No. 289,757, and it comprises a compact, highly efficient self-priming centrifugal pump capable of delivering 150 gallons per minute at 100 lbs. per square inch at the delivery end of the hose, with 75 the engine operating at 2850 R. P. M. In the

specific pump illustrated the impeller diameter is 9 $\frac{3}{8}$ " in diameter by $\frac{5}{8}$ " in width; the pump primes very rapidly, and will draw a dry vacuum of 28 inches of mercury at an elevation of 746 feet above sea level. The port arrangement and throating is shown in Figures 5 to 8, inclusive. The throat 110 of the main passageway 55, in shape is preferably that shown in Figure 7, and while it has rounded edges and rounded corners it is of the general shape of an elongated opening, the width being not substantially greater, but preferably less than the width of the channel 112 in which the impeller 46 operates. In the preferred form of throat opening as shown in Figure 7 the most constricted part of the opening between the pumping channel and the separator is at the port, that is, next to the channel, and the passageway 55 has a gradually expanding cross section into the separator. In the preferred form of throat opening shown in Figure 7 the advance end is slightly wider than the trailing end. The advance end 113 is of approximately the same width as the channel 112, whereas the trailing end is substantially narrower.

A port opening of the form shown in Figure 8 has shown excellent results but not quite as good as the form shown in Figure 7. The slot opening 110' shown in Figure 8 has a slightly constricted advance portion 113', and from there on to the rear portion 114' the port opening is of substantially uniform width less than the width of the channel 112.

As explained in my said copending application, reducing the width of the port opening to less than that of the active or effective width of the impeller, reduces the eddy current losses in the throat, allows development of a higher pressure, and markedly increases the efficiency of the pump.

It appears that the outermost high energy content layer of water is distributed along the length of the port opening instead of being all discharged at the initial part of the port opening. The pump therefore holds its pressure over a wider range of deliveries and permits the use of a smaller pump and engine in the unit, which is of a very great advantage in this particular service.

The operation of self-priming centrifugal pumps of this type is known. Suffice it to say that the pump is provided with a suitable priming charge which is trapped in the intake trap and in the impeller chamber. Upon starting of the engine, assuming that the suction hose is connected and the end thereof sealed with water to be pumped, the initial operation is to drive water into the separator 54, whereupon a part of the same returns by gravity through the passageway 56 and to the throat 115. The throat 115 is preferably of the same contour as the throat 110 or 110', inasmuch as it serves, during liquid pumping, as a discharge throat. During priming, however, the return of liquid at the throat 115 results in the impeller forming a mixture within the pumping chamber and channel and discharging the mixture of air and liquid through the discharge passageway 55 into the separator 54, where the gas is disentrained from the liquid and the liquid returns again through the return passageway 56, thereby continuously circulating and carrying out air until the desired degree of vacuum is attained, or in other words, until liquid is drawn over from the source into the pump. Thereupon, the return of liquid at the throat 115 is shut off by the pressure developed in the pumping channel and liquid is discharged in parallel

through the throats 110 and 115 into the separator 54 and from thence on out to the nozzle and is there discharged. As the pump develops suction, the return of liquid to the return passageway 56 tends to increase in rate of flow due to the difference in pressure. The discharge of mixture through the throat 110 proceeds at a higher rate unless the excess of return liquid 56 is such as to flow past the throat 110 and automatically cut off or reduce the return flow at the throat 56. This is known operation of pumps of this type.

The operation of the device as a whole is as follows: The unit, as shown in Figures 1 and 2, normally stands with liquid charged into the pump to a suitable level, which normally is not any higher than the intake connection 96. In other words, the pump contains its own charge of priming liquid prior to going into service. The closure caps 98 of the intake and 65, 65 of the discharge connections are normally in place, completely sealing off the inlet and discharge passageways of the pump so as to retain the liquid therein while the pump is standing idle and during transportation to the place of use.

If the unit is to be stored in a cold building during severe winter weather, the charge of liquid is preferably drained off through the petcocks 93 and 94, these petcocks thereafter being closed, and a charge of water containing anti-freeze ingredient is provided in a can or container which preferably is strapped in place on the frame under the intake connection 96 in such position that it cannot be dislodged during a run of the pumper. When such a can of low freezing temperature liquid is employed for the priming charge the front end of the pumper may be lowered to the ground, tipping up the intake connection, the sealing cap 98 is removed, and the liquid is poured from the container into the pump. Obviously, alternatively, the non-freezing liquid may be poured into the pump at any time before the run is made and retained in the pump without danger of freezing. When it is desired to convey the pumper to the place of use, an automobile may be backed up to the front end of the pumper. The operator then raises the rear leg 16 and locks it in raised position. The pumper is slightly overbalanced in a forward direction so that it will not tip up backwardly when the foot 16 is raised. The suction and discharge hose do not substantially unbalance the pumper fore and aft of the axle when the same are in place. By means of the handlebar 10 the front end of the frame may be raised to dispose the bumper clamp 9 over the bumper of the automobile. The clamp is then made fast, and the leg 12 is raised and locked in raised position. The unit is then ready to proceed. This may be accomplished by one man.

Obviously, if desired, the engine may be started at this time in order to warm up the engine during the run to the fire. Starting the engine prior to its arrival at the place of use is not essential. The automobile drawing the pumper may proceed at any convenient road speed, as the pumper will travel with the hauling car over substantially any road that the hauling car can travel and at almost any speed that the hauling car can attain. The driver may proceed without any attention to the unit. Upon arrival at the place of intended use, the pumper is hauled by the automobile to a point as near to the source of water as is feasible. The clamp 9 is unhooked and the pumper is pushed by hand to the desired place or location of use, whereupon the legs 12

and 16 are dropped and locked into place. This unit can readily be moved by one man on level, hard ground. The operator then starts the engine at a relatively slow speed to allow it to warm up. The associated charge of priming liquid is either introduced and is in the pump before the run is commenced, or immediately upon completing the run may be introduced as above described, and operation of the engine will not throw the same out the discharge because the valves 66 are closed and the closure caps 69 are in place. It is important to keep the shut-off valves 66 closed when the engine is started up because the engine under governor control starts with wide open throttle and jumps up to governor speed. This high acceleration up to the speed at which the engine governor is set, even if set at relatively low speed, tends to throw some of the priming water out of the discharge. The loss of priming water is undesirable as it tends to reduce or destroy the priming ability of the pump. The suction hose lengths 100 and 102 are then coupled to the intake connection 97, the cap 98 being removed, the hose couplings are drawn up tight, since air admitted to the suction is undesirable, a spanner wrench being preferably employed for that purpose. The spanner wrench may be carried in the tool box 116 (see Figure 1), a suitable box of this character being disposed on each side of the frame for carrying tools, fire nozzles and, if desired, a starting battery for the engine. As soon as the suction hose is connected and the strainer 103 covered with water to be pumped, the engine may be speeded up to prime the pump. This allows the pump to effect its prime and develop pressure while the discharge hose is being coupled. The air which is withdrawn from the suction hose and driven over into the separator is expelled through the vent pipe 59, the valve 66 preferably still being closed. While the engine is thus running to prime the pump the discharge hose may be connected to each of the branches, the sealing caps 69 being removed. Even if the pump has developed pressure, no discharge of water interferes with the coupling up of the discharge hose, because the delivery is closed off by the valve 66-66. Such closing off of the delivery of a centrifugal pump operating under pressure does it no harm, since the impeller merely slips in the impeller casing. As soon as the discharge hoses are connected and the nozzles fastened in place, the operator can see by the pressure gauge 62 whether he has delivery pressure and if the prime has been completed and pressure developed. He thereupon opens the corresponding shut-off valves 66-66, and thereupon the pumper throws water upon the fire. The governor adjustment 39 may be regulated during these operations to give the desired speed of the engine and delivery pressure of the pump.

To take the unit out of service the suction and delivery hoses are disconnected and replaced, the sealing caps are again applied, the hoses strapped down, the unit is connected to the bumper of the automobile by means of the clamp 9, the legs 12 and 16 are raised and locked in raised position, the engine being stopped in the meanwhile, and the pumper may then be run back to its shed. As soon as it is returned to the shed the pumper should be drained and cleaned out, and either provided with a fresh charge of priming liquid inside of it, or in the associated container suitably strapped into place, so as to travel with the pumper.

Now it will be observed that the maximum personnel required to hitch up, transport to the place of use, couple up the hose, open the valve, and throw water upon the fire, is one man. In brief, one man can perform in sequence all the required operations to transport the pumper to the fire, put the pumper into operation, and throw water on the fire to put it out.

A feature of prime importance is the inherent self-priming ability of the pump. When the suction hose is coupled up, and the strainer end dropped into the water, the pump will automatically pick up its prime without any attention from the operator. Also, if the suction strainer should become uncovered, or the pump should draw in air, the pump will not become air bound, but will, as soon as water is again available, pick up its prime and proceed to discharge the same.

The feature of insuring that a charge of priming liquid will be retained in or with the pumper, so that when it arrives at the place of use it will be immediately available, is important, since quite frequently it is highly inconvenient to secure any liquid to form the priming charge when the pumper is to be used. When it is desired to carry the priming charge in a separate container this container, with antifreeze liquid or any other type of liquid suitable for the conditions therein, is secured upon the frame of the pumper preferably being strapped or clamped in place under the intake nipple 96 and resting on sills 25-25. A cradle for this container may be provided if desired. Thus the charge of priming liquid is definitely associated and carried with the pump.

It is to be observed that there are no loose parts except as they are disposed in fixed relation to the unit. The device is complete and operative, even to the fireman's axe 117, which is fastened to the frame.

The pump automatically supplies itself with liquid from the source by virtue of the priming charge, but even if the priming charge were not supplied or inadvertently lost the pump might yet be primed by applying suction to the vent 59, since the discharge valves 66-66 may be closed, so that suction upon the separator 54 will be exerted through the pump to the suction hose. Such contingency is not likely to arise.

The self-priming pump is highly advantageous in picking up its own prime rapidly and efficiently, being able to handle dirty water, water with entrained solids, and to provide a satisfactory delivery at a satisfactory pressure and at high efficiency in a small, compact unit. It is also very valuable in being able to take any casual air or gas and quickly evacuate the same without being put out of operation. The priming structure does not interfere with the capacity nor limit the pumping ability of the pump, nor reduce its efficiency.

When the pumper is to be constructed to deliver pressures substantially higher than that herein disclosed it is preferable to provide a two-stage unit. Such a unit employs two or more stages in series, the final stage having the auxiliary or priming port to the periphery of the impeller in addition to the main port, and having the separator cooperating therewith. A unit suitable for this service is disclosed in my copending application Ser. No. 210,804, filed May 31, 1938, case No. 53, to which specific reference is hereby made for a detail disclosure.

The reason for going to a plurality of stages resides in this, that the center of gravity of the

pumper as a whole must be kept low so that it can travel with the hauling automobile without danger of overturning. Increases of diameter of the pump casing 45 tends to increase the weight and height of the center of gravity. While I may keep this down by making the pump casing and separator of aluminum, it tends to require raising of the crank shaft of the engine and raising its center of gravity which is undesirable. The preferred arrangement and the one which I have in the present unit been able to attain is to keep the center of gravity so low that the pumper can travel with the automobile wherever the automobile can go, and at substantially any speed the automobile can draw it.

By my invention there is provided a complete self-contained unit, large enough to be effective, i. e., capable of developing high enough pressure and throwing sufficient water to make an effective fire fighter, and at the same time, capable of use by limited personnel, if necessary, by one man.

Obviously, I do not intend to be limited to the precise details shown and described, as the pre-

ferred embodiment is but an exemplification of my invention.

I claim:

5 A self-priming centrifugal fire pump suitable for use in a mobile fire pumper comprising an impeller casing having intake and discharge passageways, an intake trap connected to the intake passageway of the casing, a separator connected to the discharge passageway of the casing, said trap having a horizontally extending suction connection provided with a quick detachable suction hose coupling, means for shutting off the suction connection to prevent loss of contained priming liquid during transport of the pump, the separator having a horizontally disposed discharge connection provided with a quick detachable discharge hose coupling, a shutoff valve between the separator and the coupling, and a restricted air vent connected to the top of the separator 10 for permitting the discharge of air from the separator while the pump is priming and the valve is closed.
